UNITED STATES PATENT OFFICE.

CURTIS E. LONG, OF CHICAGO, ILLINOIS.

DESIGN FOR A BADGE.

SPECIFICATION forming part of Design No. 22,529, dated June 13, 1893.

Application filed October 17, 1892. Serial No. 449,151. Term of patent 14 years.

To all whom it may concern:

Be it known that I, CURTIS E. LONG, a citizen of the United States, residing at Chicago, in the county of Cook and State of Illinois, 5 have invented and produced a new and original Design for a Badge, of which the following is a specification, reference being had to the accompanying drawing, forming a part thereof.

10 The leading feature of my design consists in the representation of an equilateral triangle A, and a Roman cross B, arranged within and bounded by the inner edges of the trian-

gle, substantially as shown in the drawing, which is an enlarged front elevation of my 15 badge design.

Having thus described my invention, what I claim as new, and desire to secure by Letters Patent, is—

The design for a badge, substantially as 20 herein shown and described.

CURTIS E. LONG.
